SAFETY RAZOR BLADE DISPENSER

Clarence D. Zierhut, Granada Hills, Calif., assignor to
Eversharp, Inc., New York, N.Y., a corporation of
Delaware

Application November 2, 1959, Serial No. 58,182

Term of patent 14 years

(Cl. D58—12)

Fig. 1 is a perspective view, from the top, of a safety razor blade dispenser, showing my new design;

Fig. 2 is a perspective view, from the bottom, of the dispenser;

Fig. 3 is a top plan view thereof;

Fig. 4 is a bottom plan view thereof;

Fig. 5 is a side elevational view thereof;

Fig. 6 is a front end view thereof; and

Fig. 7 is a rear end view thereof.

I claim:

The ornamental design for a safety razor blade dispenser, substantially as shown.
